COMBINED JAR LIFTER AND TOP REMOVER

Filed June 24, 1931

By Harry W. Johnson
Attorney

UNITED STATES PATENT OFFICE

JULIUS J. ELSTER, OF HILLSBORO, NORTH DAKOTA

COMBINED JAR LIFTER AND TOP REMOVER

Application filed June 24, 1931. Serial No. 546,642.

My invention relates to special tools, more particularly to a special tool for use in lifting preserving jars and for removing their tops, and it consists in the combinations, constructions, and arrangements herein shown and described.

During canning operations housewives and others often find it necessary to lift the preserving jars from hot water or raise the same under other circumstances where manual contact is impracticable. It is therefore primary purpose of my invention to provide a means for lifting preserving jars and similar receptacles without manual contact therewith.

15 A further object of my invention is to provide a device that is well adapted for the removal of caps from preserving jars or the like.

20 A still further object of my invention is to provide a device of the type described which has few parts, does not get out of order easily, and is simple to manufacture.

Other objects and advantages will appear as the specification proceeds and the device will be more particularly defined in the appended claims.

25 My device is illustrated in the accompanying drawing forming a part of this application, in which

30 Figure 1 is an elevational view showing my device in use as a jar lifter,

Figure 2 is an elevational view of my device utilized as a jar cap remover,

35 Figure 3 is a top plan view of my device in operation in accordance with Figure 2, and

Figure 4 is an elevational detail view of a portion of the device.

40 In carrying out my invention I make use of a pair of similarly formed but oppositely disposed levers, 1, pivotally interconnected as shown at 2, and having handle portions 3 and jaw portions 4. These jaw portions 4 have teeth, 5, on their inner edges for adapting the device for usage as a pair of pliers.

45 The outer extremities of these jaws 4 are equipped with upstanding portions, 6, for purposes that will soon be made clear. They are also provided with ears, 7, having eyelets, 8, therein for the reception of the end por-

tions, 9, of a looped resilient member such as a piece of spring wire, 10.

From the foregoing description the use and operation of my device is easily understood. When the operator desires to raise the jar, 55 he simply places the looped band of wire 10 about the top, 11, thereof, as shown most clearly in Figure 1, and engages the jar beneath the bead, 12, present in jars of conventional construction today, with the portions 60 on the ends of the jaws 4. He then need only take hold of the handles 3 to raise the jar. The jar will be retained in the position shown in Figure 1 under action of the force 65 of gravity, operating to secure the same between the members 6 and the looped band in a manner easily understood.

When the operator desires to utilize the device as a jar top remover, he simply positions the band about said jar top with the end portions 6 engaging the wall of the jar top in a manner shown most clearly in Figure 2. When the device is so positioned, 70 circular motion of the handle about the jar will bring about a wedging action of the cap between the looped member 10 and the wall 6 to grip the cap for the unscrewing or removing operation.

If it is desired to lift kettles or other similar receptacles, the loop is removed from the end of the levers and the device used in a manner similar to the use of a pair of pliers for raising said kettles, the projecting portions, 6, facilitating this gripping action when so used.

80 When the device is utilized as a jar lifter, a single handle having a projecting portion similar to that of 6 and eyelets for the reception of the looped band could be utilized without departing from the spirit of my invention.

85 It is thus seen that I have provided a lifter for preserving jars and the like which enables an operator to raise said jars in an easy manner without manual contact therewith.

90 It is also seen that I have provided a jar top removing device which is well adapted for gripping a threaded jar top or the like 95 for the removal thereof.

It is further seen that I have provided a device readily adapted for general usage as a lifter of kettles and similar receptacles that performs its function in a very effective manner.

What I desire to claim and secure by Letters Patent is:

1. A jar lifter and cap remover, comprising levers having handles at one extremity of each of said levers, laterally extending ears adjacent the other extremities of said levers, a loop secured to said ears for engagement about the top of the jar, and members projecting laterally from the extremities of said levers for engagement with the side wall of the jar at substantially a normal thereto, said laterally projecting members extending in a plane transverse to the planes in which said ears lie.
2. A jar lifter and cap remover, comprising a pair of similarly formed but oppositely disposed levers swivelly interconnected, laterally projecting portions at the extremity of said levers for engagement with the side wall of the jar at substantially a normal thereto, laterally extending ears adjacent said laterally extending portions, said ears lying in planes transverse to the plane in which said portions extend, and a loop having its ends secured to said levers for engagement about the top of the jar.

JULIUS J. ELSTER.
